METHOD AND APPARATUS FOR VAPORIZING
ANESTHETIZING LIQUIDSClyde B. Gardenier, Belleville, N. J., assignor to
Thomas A. Edison, Incorporated, West Orange,
N. J., a corporation of New Jersey

Application February 6, 1946, Serial No. 645,783

10 Claims. (Cl. 261—12)

1

My invention relates particularly to a novel method of and apparatus for vaporizing ether for anaesthetic purposes, and it has for an object to provide an ether vaporizer for an anaesthetizing apparatus, which is adapted to enable the ether to be administered evenly under controlled conditions at nearly room temperature.

In the anaesthetizing apparatus now commonly used, the anaesthetic is produced by bubbling air through a body of liquid ether. This air carries away the ether as it vaporizes, but it also carries heat from the liquid ether, which is the heat of vaporization absorbed by the vapor molecules, and causes the liquid ether to become intensely cold. As the liquid ether becomes colder, it chills more and more the air stream and reduces the rate of ether vaporization, causing the anaesthetic to become progressively colder and weaker. To counteract the chilling effect, the vessel containing the ether is sometimes placed on a hot plate. This heating is however ineffective to prevent the anaesthetic from yet becoming dangerously cold, and moreover it is dangerous in that it introduces a fire and explosive hazard because of the high inflammability of the ether. To compensate for the gradual weakening of the anaesthetic, it is customary to increase the rate of airflow through the liquid ether, but this has been unsatisfactory because it tends to cause the airstream to pick up particles of raw ether—i. e., unvaporized ether. When these particles come in contact with the patient they sometimes induce spasms. Because of these disadvantages in the method of administering ether as an anaesthetic not only is the patient disquieted during the anaesthesia and the length of time prolonged for treating the patient, but invariably the patient suffers from nausea as an after-effect. Also, respiratory disturbances are oftentimes induced and sometimes even pneumonia is believed to be caused by the improper condition of the anaesthetic.

It is an object of my invention to provide a vaporizer for anaesthetizing apparatus which overcomes the aforementioned disadvantages.

It has been shown by the use of my invention in hospitals that an anaesthesia can be produced quickly, safely and to any desired depth without disquieting the patient during the administering of the anaesthetic and without causing ordinarily any after-effects such as nausea or respiratory disturbances. It has been moreover shown that approximately only one-third as much ether is required to produce a given depth of anaesthesia by the use of my invention as has been heretofore

2

required. This more effective use of the ether is believed to be due to the fact that the ether is administered at nearly room temperature and in a thoroughly vaporized state. The resulting prime benefits of my invention are that the patient can be diagnosed and attended to more skillfully and in less time, and the response of the patient to the remedial measures taken is ordinarily retarded but little by the undergoing of the anaesthesia. Moreover, by my invention little ether is discharged into the surrounding atmosphere during the administering of the anaesthetic with the result that the working conditions are more comfortable for those who attend the patient.

It is accordingly a further object of my invention to provide an improved apparatus for administering ether more effectively as an anaesthetic.

Further objects and features of my invention are to provide an improved vaporizer for anaesthetizing purposes which does not require any external source of heat or power, which is easy to use and control, and which is dependable over long periods of service without need for servicing or replacing of parts; also, it is an object to provide such an improved vaporizer which has no moving parts and which is simple in its construction.

Other and allied objects and features of my invention will be apparent from the following description and the appended claims.

In the description of my invention reference is had to the accompanying drawings, of which:

Figure 1 is a partially elevational and partially axial sectional view of a vaporizer according to my invention;

Figure 2 is a sectional view taken substantially on the line 2—2 of Figure 1;

Figure 3 is a fractional axial section of the upper portion of the vaporizer;

Figure 4 is a bottom view of the air-inlet tube for the vaporizing chamber;

Figure 5 is a bottom view of a spreader tray for distributing the ether in the vaporizing chamber;

Figure 6 is an enlarged fractional sectional view taken substantially on the line 6—6 of Figure 5; and

Figure 7 is a fractional section taken substantially on the line 7—7 of Figure 2.

In Figure 1 there is shown an improved vaporizer 10 according to my invention which is adapted especially for use in anaesthetizing apparatus. This vaporizer has a container at the top for a supply 12 of the liquid to be vaporized—55 which is typically ether. At the right side of

the vaporizer there is an air-inlet tube 13 which leads downwardly into a vaporizing chamber 14 and at the left side there is an outlet tube 15 for conducting the anaesthetic, which is a mixture of air and ether vapor, to the patient.

The container 11 has a glass side wall 16 so as to enable observation of the level of the ether supply. This is a cylindrical wall clamped between flanged base and cover elements 17 and 18 which are sealed thereto by gaskets 19 (Figure 3). By way of example, the clamping is effected by a central integral stem 20 on the base element which passes through a central aperture 21 in the cover element and is secured to the cover by a nut 22 threaded onto the end portion thereof, there being a gasket 23 between the nut and cover for sealing purposes. In the cover element there is also a filler opening which is closed by a screw cap 18a.

The container 11 and vaporizing chamber 14 are joined mechanically by a heavy frame 24 which is made of a heat-conductive metal, say brass. This frame has a circular base 24a and an integral upstanding block-shaped portion 24b (Figure 2). The base element 17 seats on the block portion 24b and has a nipple 25 depending within an axial hole 26 provided in the frame. In this hole at approximately the base level of the frame portion 24b there is an annular wall 27 integral with the frame and having a central opening 28 of reduced diameter, and below this wall there is an enlarged-diameter opening 29 extending downwardly through the bottom of the frame to the vaporizing chamber and which is graduated in diameter in three steps. Threaded onto the nipple 25 is a cylindrical fitting 30 which has a reduced-diameter nipple 31 at the bottom thereof that extends through the opening 28. Threaded on this nipple 31 against the wall 27 is a nut 32 for retaining the base 17 of the container 11 to the frame.

The stem 20 has an axial hole 33 extending therethrough which communicates with the interior space of the container 11 at the bottom of the container by way of a side opening 34 (Figure 3). Below the opening 34 the axial hole 33 has a restriction forming a conoidal seat 35, and extending through the length of the stem is a needle valve 36 which cooperates with this seat. The hole 33 is slightly larger in diameter than the needle valve, but at 37 the hole is reduced to provide a seat for a packing ring 38, the hole above this reduced portion being suitably enlarged to provide a suitable space for this ring. Seated on the needle valve above the packing ring is a washer 39 and interposed between this washer and a cylindrical cap 40 that is held by screws 41 to the cover element 18 is a compression spring 42 which urges the needle valve downwardly against the seat 35 into closed position.

The cap 40 has a neck 43 which receives the needle valve and provides a bearing therefor. This neck has a transverse slit 44 extending downwardly from the top thereof which is engaged slidably by a cross pin 45 in the needle valve. This pin and slit cooperate to hold the valve fixed against rotation but to afford it an axial freedom of movement. Seated rotatably on the cap 40, and journaled on the neck 43 thereof, is a manual adjusting member 46 which has a circular cam face 47 at the top thereof. This cam face lies in a plane which is oblique to the axis of the needle valve as indicated in Figure 1. Locked to the needle valve by the pin 45 is a cylindrical member 48 having a cir-

cular cam face 49 at the bottom thereof. This cam face 49 is also in a plane oblique to the axis of the needle valve and rests slidably on the cam face 47. The manual member 46 has a knurled peripheral portion so that it can be readily gripped and adjusted, and has a depending annular flange 46a provided with graduations 50 which, with respect to a registering mark 51 on the base of the cap 40, provide a visual indication of the adjusted positions of the needle valve. For example, when the member 46 is in the zero position indicated in Figure 1, the needle valve is held closed by the spring 42, but as the member 46 is turned progressively through a range of 180° the inclined cam faces 47 and 49 coact to lift the valve progressively from the seat 35 and allow the ether to escape at a faster rate from the container 11.

To permit observation of the rate at which the ether is escaping from the container 11, the block-shaped frame portion 24b and the fitting 30 have respective windows 52 and 53. The fitting is however closed by a glass tube 54 therewithin which is clamped at the lower end thereof against the bottom wall of the fitting and at the upper end against the nipple 25 by a tightening of the fitting onto the nipple. For sealing purposes there are gaskets 55 placed at the ends of the glass tube 54 as shown in Figure 3.

The vaporizing chamber 14 is formed by a vessel 56 which engages telescopically with a depending circular flange 57 on the frame 24. This vessel has an interior collar 58 secured thereto near the top thereof which is clamped by screws 59 (Figure 2) to the frame. Between this collar and the flange 57 there is a gasket 60 for sealing purposes.

The ether is conducted downwardly from the observation chamber in the tube 54 by a tube 61 that is threaded interiorly into the nipple 31 (Figure 3). This tube 61 has the lower portion thereof flared outwardly at a wide angle to provide a baffle 62 as is hereinafter explained. Below this baffle 62 there is a circular spreader tray 63 which is fitted into the largest-diameter portion of the stepped opening 29 aforementioned. This tray has a series of spaced apertures 64 (Figure 5) which are formed preferably by perforating the tray at the bottom side with a pointed instrument so as to raise a burr or flange 65 around each aperture having a jagged top edge 66 as shown in Figure 6. When the ether drops onto the tray and rises to the level of the lowermost portions of these edges 66, it overflows through the apertures into the vaporizing chamber. When the vaporizer is mounted so that the tray is substantially on a level with the horizontal, about equal amounts of ether flow through the respective apertures to cause the ether to be distributed across the top of the vaporizing chamber.

Air from any suitable source not herein necessary to show is conducted to the vaporizer by the tube 13 fractionally shown and thence by a nipple 67 to a cylindrical chamber 68 in the block portion 24b of the frame. In one end of this chamber there is a safety release valve 69 which is adapted to prevent the air pressure to the vaporizer exceeding a set value. In the other end of this chamber there is a valve 70 having a tubular housing 71 that is press-fitted into the chamber. This housing has a circumferential slot 72 (Figure 7) which communicates with a duct 73 leading down from the chamber 68 through the frame. Rotatably fitting the housing 71 and 75 extending therethrough is a valve member 74

which has an annular shoulder 75 bearing rotatably against the outer end of the housing 71 under pressure of a nut 76 threaded on the inner end of the valve member and acting through a spring washer 77 against the inner end of the housing. This valve member has an axial opening 78 communicating with the chamber 68 and branching out into a series of circumferentially-spaced radially-extending holes 79 to 82 inclusive, which holes are graduated in diameter as shown in Figure 7. On the outer end of the valve member there is a knurled knob 83 by which the valve member can be turned to bring the holes 79-82 selectively into registration with the duct 73 and control thereby the rate of airflow to the vaporizer.

The duct 73 has a lower end portion of enlarged diameter (Figure 1) into which there is fitted a tube 84. This tube extends downwardly to the bottom of the vaporizing chamber 14 and terminates in a horizontal spiral that is closed at its inner end 85 and provided with a series of outlet openings 86 at the bottom thereof as shown in Figure 4.

The dispersed air from these spaced outlet openings passes upwardly through a channeled mass 87 in the vaporizing chamber, which is hereinafter described in detail, and passes out of the vaporizing chamber through the apertures 64 of the spreader tray 63. Above the tray the air takes a circuitous path 88 defined by the baffle 62 aforementioned and a cooperating baffle 89 which is concentric therewith as shown in Figure 1. This path 88 leads upwardly and radially inwardly to the uppermost part of the stepped opening 29 and then downwardly and radially outwardly above the baffle 89 to an outlet duct 90 in the frame 24. This baffling is provided as a safety measure to prevent the outgoing airstream from carrying with it any particles of raw ether.

The duct 90 leads to the outgoing tube 15 aforementioned to which it is connected by a nipple 91 that is threaded into the block-shaped portion 24b of the frame. Leading also from this outgoing duct, however, is an upwardly-extending duct 92 to which is connected a vertical tube 93 that opens at the top of the container 11. The purpose of this tube 93 is to equalize the pressure above the ether supply with that at the outlet of the container so that when the needle valve 36 is opened the ether will escape from the vessel under the influence of gravity.

As an important feature of my invention, I select a porous material for the mass 87 which has a high adsorptivity for the liquid to be vaporized. This is done so that a source of immediate heat, a heat of adsorption, is provided to counteract the refrigerating effect produced by the ether as it vaporizes and to facilitate the vaporization of the ether. First, it may be noted that the term "channeled" is herein employed to mean that the mass has multitudinous interconnected channel spaces or interstices running therethrough such as may be formed in a solid integral mass or as occurs in a granular mass of discrete particles. Preferably, materials in granular form are employed. Suitable examples of such materials are the activated porous solids such as of carbon, alumina, silica gel and clays, but carbon is preferred. As a typical example, the vaporizing chamber may have 72 cubic inches of volume and may contain 14 ounces of porous granulated carbon.

The ether which drops into the vaporizing

chamber contacts a vast surface area of the channeled carbon mass 87 and a portion thereof is adsorbed by this mass. Also, the ether has a large area of surface contact with the multitudinous air streams flowing upwardly through the channeled mass, which causes the ether to be readily vaporized. As portions of the ether are progressively adsorbed there is released a heat of adsorption in the vaporizing chamber, which is about 30 calories for each gram of ether adsorbed. This heat is immediately available for counteracting the heat loss caused by the heat of vaporization absorbed by the ether as it vaporizes. As beneficial results the vaporization of the ether is facilitated and the ether is delivered to the patient at a moderate temperature and with more effective action so that less ether is required.

As a means of stabilizing further the temperature of the anaesthetic, I add a further source 20 of immediately available heat to the vaporizer by placing the vaporizing chamber in close thermal contact with a body 94 of a crystallizable liquid having a temperature of crystallization at approximately room temperature, say 25° C. This 25 is done by providing a vessel 95 around the vaporizing chamber and filling the space between these vessels with the crystallizable liquid. This outer vessel may telescope with a depending annular flange 96 of the frame 24 and may have an interior collar 97 secured thereto which is clamped by screws 98 to the frame, the vessel being sealed to the frame by a gasket ring 99 placed between the collar 97 and flange 96. For filling purposes there is a screw plug 100 in the frame 24 leading 30 to the space between the vessels 95 and 96.

In order that there may be good heat conduction between the outside ambient and the vessel 95 as well as between the body of liquid 94 and the vaporizing chamber, the vessels 95 and 56 40 and the frame 24 are made of a heat-conductive material such as brass. Also, such material has a high heat capacity, which has a further temperature-stabilizing effect on the anaesthetic. For example, the vessels 95 and 56 and the frame 24 weigh typically approximately 5,000 grams and provide about 4,500 calories of sensible heat as the temperature thereof drops about 10° C.

The liquid 94 is chosen to have a high heat of crystallization and may be suitably any one or a mixture of the following: tertiary butyl alcohol, 50 diphenyl methane, isoquinoline, phenyl ether, terpineol or methyl anthranilate. Considering tertiary butyl alcohol, for example, it may be noted that 1,000 grams of this liquid will release 21,900 calories of heat as the liquid crystallizes.

The improved operation of my vaporizer over the method heretofore used may be strikingly noted by citing the results of the following tests: On vaporizing ether by the bubbling process with the use of a Sklar machine, with the air being initially at a temperature of 25° C. and passed at a rate of 10 liters per minute through 320 cc. of liquid ether initially at a temperature of 25° C., it is found that in five minutes 82 cc. of ether are vaporized and the temperature of the anaesthetic has fallen to 6° C. below zero. In ten minutes 122 cc. of ether are vaporized and the temperature has fallen to 14° C. below zero, and in fifteen minutes 147 cc. of ether are vaporized and the temperature has fallen to 17° C. below zero. Thus the anaesthetic has not only become intensely cold, so cold as to be dangerous to the patient, but the rate of vaporization has fallen off substantially, it being 82 cc., 40 cc., and 25 cc., respectively for the successive five-minute intervals,

By contrast, with my invention ether may be vaporized at a fixed rate for periods of at least thirty minutes or more without any decrease at all in the temperature of the resulting anaesthetic emitted from the vaporizer throughout such period. Purely by way of example, it may be noted that for a given setting of the valve 36, and on passing air through the vaporizer at a rate of 10 liters per minute, with the air at a temperature of 29° C., 300 cc. of ether may be vaporized in fifteen minutes and the temperature of the anaesthetic at the end of this period is yet 29° C. For smaller rates of vaporization the temperature of the anaesthetic may even rise somewhat during the initial part of a period of use of the vaporizer. By actual use of this vaporizer in hospitals it has been shown that in view of this improved action—i. e., more thorough vaporization and stabilized temperature—the amount of ether required varied from 70 cc. to 200 cc. as against amounts of 300 cc. to 680 cc. by the bubbling method as now used. Also, it was found that anaesthesia was induced more quickly and smoothly, without coughing or gagging, and that the depth of the anaesthesia was more easily controlled. Also, the patient recovered more quickly from anaesthesia without the usual after-effects of nausea and respiratory disturbances.

It will be understood that the absorptive and crystallizing process above described by which heat is liberated to the anaesthetic will not go on continuously, should the apparatus be used without interruption over a long period, because in time the granular mass 87 would become saturated with ether and the liquid 94 would become wholly crystallized. It is found in actual use however that the vaporizer will operate continuously at near peak efficiency for at least a period of about eight hours. After such prolonged use the activated carbon seems dry to the touch but has a strong odor of ether. To free the carbon of this adsorbed ether, the air supply to the vaporizer is turned on to circulate air through the vaporizing chamber at a fairly rapid rate for a short period, a period of 5 to 10 minutes being generally sufficient to recondition the carbon mass for another prolonged usage of the vaporizer. To recondition the liquid 94, heat may be added from any suitable source. If, however, the vaporizer may be let stand overnight in air at room temperature, the liquid 94 will absorb sufficient heat from the surrounding atmosphere to melt and become again a source of heat supply. It will be understood that these reconditioning operations may be repeated again and again without need for replacing the adsorbing mass 87 or the liquid 94. Because the heat is obtained without the use of any external source of intense heat, my vaporizer is utterly safe against any hazard of fire or explosion. Also, my invention can be used in out-of-the-way places, if necessary, because it requires no source of electric power.

In practical use, the anaesthetist predetermines the airflow rate for each patient and sets the airflow through the vaporizer at that rate. Next, he meets the anaesthetic demands by adjusting the needle valve 36. Except for the ether which is adsorbed, substantially all of the ether which is released by the valve 36 is vaporized; as a result, the anaesthetist may control the degree of anaesthesia by adjusting merely the valve 36. Typically, the valve is first opened sufficiently to supply the higher initial demands for the

anaesthetic until the patient undergoes anaesthesia, and then the valve is closed partially to supply only enough ether to maintain the desired depth of anaesthesia. During the initial period when the liquid ether is fed to the porous mass 87 at the higher rate, progressive adsorption of the liquid occurs to provide a continuous supply of heat to the anaesthetic, as heat of adsorption, but during the stand-by periods when only little or no liquid ether is fed to the porous mass 87, the air which is blown through the mixing chamber to supply the oxygen demands of the patient does gradually carry away the adsorbed liquid to desorb the porous mass 87. Typically, the stand-by period is sufficiently long to cause the porous mass to be fully restored to its unsaturated condition. This restoration occurs without reducing substantially the temperature of the air during the stand-by period since the desorption takes place gradually. Thus, in normal use, the porous mass 87 provides a high rate of available heat during the temporary periods when the anaesthetic demands are greatest, to aid during those periods in thoroughly vaporizing the anaesthetizing liquid and in keeping the anaesthetic gas at or near body temperature, and during the stand-by periods this mass is restored to well-nigh its full adsorptive capacity. As a result, in the normal use of the apparatus no special deliberate reconditioning of the porous mass is ever necessary.

While I have herein particularly described an embodiment of my invention for anaesthetizing purposes with ether as an anaesthetic, it will be understood that my invention has advantages as a vaporizer of other volatile anaesthetizing liquids and that I intend no unnecessary restriction of my invention to the specific embodiment herein described. Also, it will be observed that changes and modifications may be made in this embodiment without departing from the scope of my invention, which I endeavor to express according to the following claims.

I claim:

1. In apparatus for vaporizing liquid for anaesthetic purposes, comprising a vaporizing chamber: the combination of a porous channeled mass of material in said chamber capable of adsorbing said liquid, means for introducing air into said chamber at a plurality of spaced points below said mass, an apertured means at the top of said chamber, means for dropping liquid onto said apertured means, said liquid passing through said apertured means under the influence of gravity and falling onto said mass at distributed points, and an outlet for conducting the air and vaporized liquid from said chamber, said outlet being in communication with said chamber by way of said apertured means.

2. The method of producing an anaesthetizing gas at moderate temperature for a given period of time, which comprises feeding a volatile anaesthetizing liquid gradually to a mass of porous material capable of adsorbing said liquid and producing a heat of adsorption, and passing a stream of air through said porous mass to carry off vapor of said liquid at a lesser rate than that at which the liquid is fed thereto, whereby there is a progressive increase of adsorbed liquid in said material during said period, and also to carry off the heat of adsorption, said porous material being of a sufficient quantity that it remains in subsaturated condition throughout said period.

3. In the operation of an anaesthetizing machine: the steps comprising gradually feeding a

volatile anaesthetizing liquid to a porous mass of a material capable of adsorbing the liquid and producing a heat of adsorption, simultaneously passing air through said mass to carry off vapor of said liquid at a lesser rate than that at which the liquid is fed thereto and to carry off also said heat of adsorption to provide an anaesthetizing gas at moderate temperatures, and then reconditioning said porous mass for further adsorption of said liquid, only by blowing air through the mass.

4. In the administration of an anaesthetic: the method comprising feeding a volatile anaesthetizing liquid to a porous mass of a material capable of adsorbing said liquid and producing a heat of adsorption, simultaneously passing a stream of air through said mass to carry off vapor of said liquid and said heat of adsorption to produce an anaesthetizing gas at moderate temperature, said porous mass being of sufficient quantity that the same remains in a subsaturated condition during the period of administration of the anaesthetic, and conducting said anaesthetizing gas from said porous mass through a circuitous path having free drainage to the porous mass.

5. An anaesthetizer adapted for producing an anaesthetizing gas at moderate temperature at least throughout a normal period required to effect an anaesthesia, comprising a container for a volatile anaesthetizing liquid; a chamber containing a porous mass of a material capable of adsorbing said liquid and producing a heat of adsorption; means for feeding liquid from said container to said porous mass at a rate in excess of that at which the liquid is adsorbed by said porous mass to provide a normal supply of vapor of said liquid for anaesthetizing a patient; and means for passing air through said mass to carry off said vapor and heat of adsorption to provide an anaesthetizing gas for a patient at a normal rate, the quantity and porosity of said mass of adsorptive material being such that upon supplying said liquid and air thereto at said rates the material remains in a subsaturated condition during said period of use and the temperature of the anaesthetizing gas is held substantially constant during said period.

6. An anaesthetizer for producing an anaesthetizing gas at moderate temperature comprising a container for a volatile anaesthetizing liquid, a vaporizing chamber containing a granulated porous material capable of adsorbing said liquid and producing a heat of adsorption, a tray at the top of said chamber having apertures in the outer portion thereof, a tube leading from said container for dropping said liquid gradually onto the central unapertured portion of said tray whereby the liquid spreads over the tray and drops through said apertures onto said adsorbing material, means at the bottom of said chamber for blowing air upwardly through said porous adsorbing material to carry off vapor of said liquid and said heat of adsorption to produce an anaesthetizing gas at moderate temperature, an outlet for said chamber having a circuitous path with free drainage to said chamber, and a cham-

ber immediately surrounding said vaporizing chamber and containing a crystallizable liquid which crystallizes substantially at room temperature to provide a heat of solidification to said vaporizing chamber as the temperature in the latter tends to fall below room temperature.

7. In the method of producing an anaesthetizing gas: the steps comprising gradually feeding a volatile anaesthetizing liquid to a porous material capable of adsorbing the liquid and producing a heat of adsorption, simultaneously passing a stream of air through said porous material to carry off vapor of said liquid at a lesser rate than that at which the liquid is fed to said porous material and also to carry off heat of adsorption, and then further passing air through said porous material sufficiently to gradually desorb the same.

8. The method of producing an anaesthetic gas at moderate temperature which comprises volatilizing an anaesthetizing liquid and simultaneously producing heat in intimate thermal relation with the gas so produced by gradually feeding said anaesthetizing liquid to a material having a high adsorptive affinity for said liquid and being in an adsorptively unsaturated condition whereby a portion of the liquid so fed to said material is adsorbed to produce a heat of adsorption and passing air across said material to carry off said heat of adsorption and volatile gases of another portion of the liquid so fed to said material.

9. An anaesthetizing device comprising a vaporizing chamber, means for blowing a stream of air into said chamber, means for feeding a volatile anaesthetizing liquid into the air stream within said chamber, and means in the air stream within said chamber responsive immediately to contact of said liquid therewith for producing heat in immediate transfer relation with said air stream.

10. An anaesthetizing device comprising a vaporizing chamber, means for blowing a stream of air through said chamber, means for feeding a volatile anaesthetizing liquid into said chamber including means for distributing liquid through said air stream, and a porous mass within said chamber and responsive to contact of said liquid therewith for producing an immediate heat in said chamber throughout said air stream.
